UNITED STATES PATENT OFFICE.

ALTON B. HEIMBACH, OF DULUTH, MINNESOTA.

ATTACHING DEVICE FOR RUBBER HEELS.

1,064,212.

Specification of Letters Patent.

Patented June 10, 1913.

Application filed September 18, 1911. Serial No. 649,783.

To all whom it may concern:

Be it known that I, ALTON B. HEIMBACH, a citizen of the United States, residing at Duluth, in the county of St. Louis and State 5 of Minnesota, have invented certain new and useful Improvements in Attaching Devices for Rubber Heels, of which the following is a specification.

My invention relates to an improvement 10 in attaching devices for rubber heels and is particularly designed for the provision of a plate for attachment to the heel lift to facilitate the application of a rubber heel in such a manner that there will result an 15 increased rigidity of connection between the heel lift and the rubber heel.

My invention aims to effect this increased 20 rigidity of connection with a plate of such form that the cavity provided in the rubber heel for the reception thereof, may be formed by the removal of a minimum amount of material from the rubber heel. The most efficacious way of attaining this 25 result, has been found to be the provision of a connection which is somewhat in the nature of a dove-tail joint.

The preferred embodiment of my invention is shown in the accompanying drawings, in which—

30 Figure 1 is a partial view of an inverted shoe showing my improved plate attached to the heel lift thereof, Fig. 2 is a top plan view of my attaching plate, Fig. 3 is a top plan view of the rubber heel showing, in 35 plan, the form of cavity for the reception of the plate and showing the plate contained therein, Fig. 4 is a longitudinal section taken on line 4—4 of Fig. 3, and, Fig. 5 is a transverse section taken on line 5—5 of Fig. 3.

40 The plate utilized by me, desirably comprises a main rectangular or square portion 1 having nail or screw holes 2 and having a triangular flange 3 surrounding all sides thereof and formed integrally thereon. The 45 rear end of the flange 3 is rounded as at 4 to the same general contour as the rear of the heel.

The heel is desirably provided with a square opening 5 substantially the size of

the body portion 1 of the plate and merging at its rear end into a transverse slot 6. Upon the forward edge and the side edges of this opening, the walls thereof are undercut as shown in dotted lines and are substantially triangular to receive the plate 3. The 55 rear wall of the slot 6 is likewise undercut and of a contour to conform to the rear shelf and edge 4.

It will be seen that my heel is applied by first attaching the metal plate to the heel 60 lift in the manner shown in Fig. 1 and then inserting the forward end of the plate into and through the slot 6 and passing the shelf upon the plate forwardly into the rubber heel. Then, the rear edge of the shelf is in- 65 inserted in the undercut cavity to the rear of the slot 6.

From the above, it will be seen that I have provided a rubber heel of a peculiar form and a plate particularly constructed for the 70 connection thereof to the shoe heel, which serves to hold the rubber heel firmly upon the heel lift upon all sides thereof. The material cut from the rubber is compara- 75 tively small in quantity and the structure is such that there is an even retaining effect upon the rubber heel at all points thereof.

What I claim, is—

The combination with a rubber heel having a cavity in the top thereof, said cavity 80 having its side walls downwardly and outwardly inclined, and said heel having an entrance slot leading into said cavity, of an attaching plate adapted to fit within said cavity, said plate having its side walls down- 85 wardly and outwardly inclined to correspond with the side walls of said cavity, said plate having its rear inclined wall curved to correspond to the curvature of the rear end of the heel, and said plate having a rela- 90 tively large centrally located aperture therethrough to reduce the weight of said plate.

In testimony whereof I affix my signature in presence of two witnesses.

ALTON B. HEIMBACH.
